UNITED STATES PATENT OFFICE.

ROBERT DUDLEY CARTER, OF BROADLEATH, ENGLAND, ASSIGNOR TO LINOTYPE AND MACHINERY LIMITED, OF LONDON, ENGLAND.

DISTRIBUTING MECHANISM OF TYPOGRAPHICAL COMPOSING AND CASTING MACHINES.

1,427,517.

Specification of Letters Patent. Patented Aug. 29, 1922.

Application filed May 4, 1921. Serial No. 466,845.

To all whom it may concern:

Be it known that I, ROBERT DUDLEY CARTER, a subject of the King of the United Kingdom of Great Britain and Ireland, and residing at Linotype and Machinery Works, Broadheath, in the county of Chester, England, have invented new and useful Improvements in or Relating to the Distributing Mechanism of Typographical Composing and Casting Machines, of which the following is a specification.

This invention relates to improvements in the distributing mechanism of typographical composing machines such as those known commercially under the trade mark "Linotype." More particularly it relates to that type of such machines which is equipped with a plurality of magazines containing matrices of respectively different fonts or faces, adjustable as a whole to bring different pairs of them into operative relationship with two font distributors.

Machines of this kind are known in which the distribution of matrices to the pair of magazines in operative relationship to the two distributors which are arranged one above the other, is effected by means of a fixed central rail located at the receiving end of the upper distributor. The matrices of the upper magazine of the pair are provided with a central notch, while those for the lower magazine are unnotched and on being presented to the distributor, the notched matrices drop down over the central rail sufficiently to prevent them from being engaged by the upper distributor bar, and after passing over the rail they drop into a chute which conducts them to a distributor or separator box, wherein in well-known manner, they are separated and allowed successively to engage with the lower set of distributor screws by which they are distributed to the upper magazine. On the other hand, the unnotched matrices intended for the lower magazine of the pair are supported by the central rail at a level which enables them to engage the upper distributor bar whereby they are distributed to the lower magazine. This method of distribution, however, limits the possible use of the magazines in the column to a number of successive pairs, the magazines containing alternately unnotched and notched matrices;

that is to say, in a machine of this construction provided with four magazines, only two pairs comprising respectively the first and second, and the third and fourth of the magazines, can be simultaneously operated, since the distributor is only able to direct a notched matrix to the upper magazine and an unnotched matrix to the lower magazine, and its selective function has not been variable to permit of a reversal of this order of delivery.

It has been proposed to increase the range of utility of such machines by substituting for the fixed central rail a series of font-selecting bridges of known type, each provided with a distinctive combination of ridges corresponding to distinctive notches in the feet of matrices in a respective magazine, and providing means whereby the location of any magazine in the upper operative position, renders operative the particular bridge corresponding to the matrices contained in that magazine, thus enabling the distributors to work in conjunction with any two successive magazines.

The object of the present invention is to secure the desired variability of the selective function of the distributor, by a simpler construction. To this end, the fixed central rail above referred to, is substituted by a movable rail or rails adapted to occupy in the path of the matrices being presented to the distributor, two distinct positions in relation to the feet of the matrices, means are provided acting by or through the adjustment of the magazine column for moving the said rail to and retaining it in one or other of its two positions, and the feet of the matrices for the respective magazines are appropriately notched in a manner such as that hereinafter more particularly referred to.

A preferred constructional form of the invention is illustrated in the accompanying drawings, in which:

Figure 1 is a front elevation of a portion of the distributing mechanism and adjacent parts of the machine;

Figure 2 is a right-hand side elevation of Figure 1, shown partly in section;

Figure 3 illustrates matrices suitably notched for co-operating with the constructional form of selector-bridge shown in Figures 1 and 2.

Fig. 4 is an enlarged transverse section showing in detail the mounting for the selector-bridge.

The general construction of the machine 5 in connection with which the invention is illustrated in the drawings is of known form, the magazines 1, 2, 3, 4 being adjustable columnwise (as by lever-actuated links of which only one, 78, is shown in the drawings) relatively to the two distributors 5, 6, to the latter of which matrices are conducted from the former by the transfer chute 7.

According to the present invention, an adjustable font-selector bridge 8 is provided 15 which, in the constructional form now being dealt with, has two rails or ridges 30 in a position to engage the feet of the matrices as the latter leave the distributor box 61, and is rigidly attached to a rod 128 slidably 20 mounted between the front bottom rail 131, and rear bottom rail 132 of the distributor box 61. The rod 128 is formed with a shoulder 128^a against which the bridge piece 8 is held by a collar 128^b secured to the end 25 of the rod 128, the bridge piece being held vertical by a pin 128^c driven into side rails 131 and 132 and passing loosely through the bridge piece to allow the latter to slide freely thereon when moved from one position 30 to the other. The rod 128 is extended towards the front of the machine, passing through a guideway provided for it in the lower distributor beam 134 or a suitable part of the machine frame 12, and is preferably 35 fitted with a turn-buckle 135 whereby its effective length can be adjusted to regulate the operative positions of the bridge 8. The rod 128 is arranged to slide fore-and-aft of the machine under the control of the movement 40 of the magazines, for which purpose it may be conveniently connected, on the front side of the beam 134, to one arm 136 of a bell-crank lever pivoted to a bracket 137 on the beam 134, the other arm 138 of which 45 lever is connected by a link 139, to a second lever 140, 141, pivoted at 142 to a bracket 143 secured to the machine frame 12. The arm 141 of the last mentioned lever carries a roller 144, which is normally retained, by 50 a tension spring 145 acting on the link 139, in the path of a cam-block 146 secured to the adjacent side of the column of magazines. The location of the cam-block 146 is such that when the two upper magazines 1 and 2 55 are in the operative position, as shown in the drawings, the lever 140, 141, and the lever 136, 138, will be held, under the control of the spring 145, in the position in which they are shown in full lines in the 60 drawings, while movement of the magazine column to bring the second pair 2 and 3, of magazines to the operative position, will cause the roller 144 to ride over the upper cam face 147 of the block 146, and to be 65 held in the position in which it is shown in

dotted lines in Figure 2. On further movement of the magazine-column to its uppermost position indicated by dot-and-dash lines in Figure 2, in which position the third pair, 3 and 4, of the magazines are in operation, the roller 144 will ride down the lower cam face 148 and again occupy its normal position under the control of the spring 145. Thus, when either of the pairs of magazines 1 and 2 or 3 and 4 are in operation, the selector bridge 8 will occupy its rearward position with its rear face in contact with the rear bottom-rail 132 of the distributor box 61, as shown in Fig. 2, but the bringing into operation of the middle pair of magazines, 2 and 3, will cause the bridge 8 to be moved to and held in its frontward position with its front face in contact with the front bottom-rail 131, as shown in Fig. 4.

Matrices 133, 133^a, suitable for use with the above-described font-selector bridge, are illustrated in Figure 3. It is to be noted that both such matrices have their two font-distinguishing notches 29 at the same distance part, corresponding with the distance 85 separating the two ridges 30 on the font-selector bridge, but the notches 29 of a matrix 133 are differently located with reference to the centre line of the matrix as compared with those of a matrix 133^a, the arrangement being such that notches 29 of matrices 133 will register with the ridges 30 only when the selector-bridge 8 is in its rearmost position under the control of the spring 145, and the notches 29 of matrices 133^a will register with those ridges only when the selector-bridge 8 is in its foremost position under the control of the cam block 146.

In carrying out the invention, matrices 105 such as 133 are contained in alternate magazines commencing with the uppermost of the column, magazines 1 and 3 in the example illustrated, while matrices 133^a are stored in the remaining alternate magazines, e. g., 2 and 4, and distribution will therefore be accurately effected to the two magazines of any pair which may be in operative position. For instance, when, as illustrated in the drawings, magazines 1 and 2 constitute 110 the operative pair, the selector-bridge 8 is in its rearmost position under the control of the spring 145. Under these conditions, matrices 133^a appropriate to magazine 2 will travel over the ridges 30 and be delivered to that magazine by the upper distributor 5, while matrices 133 appropriate to magazine 1, whose notches 29 correspond with the then position of the ridges 30, will straddle those ridges and be delivered 115 through the chute 7 to the lower distributor 6 and thence to the magazine 1. As explained above, the bringing into operation of magazines 2 and 3 will cause the bridge 8 to take up its foremost position. Matrices 130

133^a will then straddle the ridges 30 and consequently will be conveyed through the chute 7 to the lower distributor 6 which is then serving the magazine 2, while matrices 5 133 appropriate to the magazine 3 will ride over the ridges and be dealt with by the upper distributor 5 then serving that magazine. As the magazines 3 and 4 contain matrices 133, 133^a respectively corresponding 10 with those in magazines 1 and 2, and the position of the bridge 8 is the same for the operation of either of the two pairs of magazines 1 and 2, or 3 and 4, it will be understood that the distribution will be accurately effected for the last pair of magazines in the same manner as for the first pair. All matrices for the magazines 1, 2 and 3, must have, in addition to the special font distinguishing notches 29, the usual 15 central separating notch 149, seeing that each of those magazines is, in turn, served by the lower distributor 6 and the matrices therefore have to be dealt with by the known separator box; but as the lowermost magazine 25 4 of the column is only served by the upper distributor, such central notch is not essential to the matrices stored therein, though it may be convenient to provide same to permit of the magazine being used in a 30 different position in the column if it should at any time be desired to so use it.

The above described constructional form may, obviously, be considerably varied without departing from the essential features of 35 the invention. For example, suitable means, other than those illustrated, may be provided for effecting the adjustment of the selector-bridge, and the latter may, if desired, have only a single ridge or rail, in which case the 40 matrices in alternate magazines of the column would be provided with single font-distinguishing notches at respectively opposite sides of their feet. Even in the last-mentioned form, it will be recognized that 45 the invention is clearly distinguished from the known type of adjustable font-distinguishers which have been employed in connection with the distribution of matrices to a single magazine and which operate by arresting on its passage to the distributor any 50 matrix not appropriate to the magazine in operation, seeing that the function of the last-mentioned devices is essentially rejective, and that the said devices are inapplicable to the selective function called for by 55 the present invention.

It is pointed out that the term "font" is not used herein in any limiting sense but only in a general descriptive way. For instance, when in the appended claims the 60 magazines are referred to as adapted to contain matrices of respectively different fonts, it is to be understood that this is intended to embrace matrix sets of different form and 65 quite irrespective of the size or style of the

matrices stored in the different magazines.

Having described my invention, I declare that what I claim and desire to secure by Letters Patent is:—

1. In a machine such as described, the 70 combination with a column of magazines adapted to contain matrices of respectively different fonts, two distributors adapted to distribute matrices simultaneously to two adjacent magazines, and magazine-moving 75 means adapted to bring the magazines successively into operative relationship with the distributors, of a font-selector bridge adapted to determine the level at which matrices pass a given point in their path towards the distributors, and means controlled through the operation of the magazine-moving means adapted to move the bridge to different operative positions. 80

2. In a machine such as described, the 85 combination with a column of magazines adapted to contain matrices of respectively different fonts, two distributors adapted to distribute matrices simultaneously to two adjacent magazines, and magazine-moving 90 means adapted to bring the magazines successively into operative relationship with the distributors, of a font-selector bridge adapted to determine the level at which matrices pass a given point in their path towards the distributors, and means controlled through the operation of the magazine-moving means adapted to move the bridge to two different operative positions alternately as the successive magazines are moved into 95 operative relationship with the distributors. 100

3. In a machine such as described, the 105 combination with a column of magazines, two distributors adapted to co-operate simultaneously with two adjacent magazines and magazine-moving means adapted to bring the magazines successively into operative relationship with the distributors, of a ridged font-selector bridge adapted to cooperate with notched matrices to determine the level 110 at which such matrices pass a given point in their path towards the distributors, means controlled through the operation of the magazine-moving means adapted to move the bridge to two different operative positions alternately as the successive magazines are moved into operative relationship with the distributors, and matrices in alternate 115 magazines notched to pass the said given point at one level when the bridge is in one 120 operative position and at another level when the bridge is in the other operative position. 125

4. In a machine such as described, the combination with a column of magazines, two distributors adapted to co-operate simultaneously with two adjacent magazines and magazine-moving means adapted to bring the magazines successively into operative relationship with the distributors, of a ridged font-selector bridge adapted to co- 130

1
operate with notched matrices to determine the level at which such matrices pass a given point in their path towards the distributors, means controlled through the operation of 5 the magazine-moving means adapted to move the bridge to two different operative positions alternately as the successive magazines are moved into operative relationship with the distributors, and matrices in successive 10 magazines notched to pass the said given point at one and the same level when the bridge is in the operative position determined by the movement of the respective magazine into operative relationship with 15 one of the distributors.

5. In a machine such as described, the combination with a column of magazines, two distributors adapted to co-operate simultaneously with two adjacent magazines 20 and magazine-moving means adapted to bring the magazines successively into operative relationship with the distributors, of a ridged font-selector bridge adapted to co-operate with notched matrices to determine 25 the level at which such matrices pass a given point in their path towards the distributors, means controlled through the operation of the magazine-moving means adapted to move the bridge to two different operative 30 positions alternately as the successive magazines are moved into operative relationship with the distributors, and matrices in successive magazines notched to pass the said given point at one and the same level when 35 the bridge is in the operative position determined by the movement of the respective magazine into operative relationship with one of the distributors, and at another level when the bridge is in the operative position 40 determined by the movement of the respective magazine into operative relationship with the other of the distributors.

6. In a machine such as described, the combination with a column of magazines 45 adapted to contain matrices of respectively different fonts, two distributors adapted to distribute matrices simultaneously to two adjacent magazines, and magazine-moving means adapted to bring the magazines successively 50 into operative relationship with the distributors, of a font-selector bridge adapted to determine the level at which matrices pass a given point in their path towards the distributors, a sliding member 55 to which the bridge is rigidly attached, means adapted to slide said member in one direction and to normally retain the bridge in one operative position, and means operated through the movement of alternate 60 magazines into operative relationship with the distributors adapted to slide said member in the opposite direction to locate the bridge in another operative position.

7. In a machine such as described, the 65 combination with a column of magazines,

two distributors adapted to co-operate simultaneously with two adjacent magazines and magazine-moving means adapted to bring the magazines successively into operative relationship with the distributors, of a ridged font-selector bridge adapted to co-operate with notched matrices, to determine the level at which such matrices pass a given point in their path towards the distributors, a sliding member to which the bridge is 70 rigidly attached, means adapted to slide said member in one direction and to normally retain the bridge in one operative position, means operated through the movement of alternate magazines into operative relationship with the distributors adapted to slide said member in the opposite direction to locate the bridge in another operative position, and matrices in alternate magazines notched to pass said given point at one level 75 when the bridge is in the first-named operative position and at another level when the bridge is in the second-named operative position.

8. In a machine such as described, the combination with a column of magazines, two distributors adapted to co-operate simultaneously with two adjacent magazines and magazine-moving means adapted to bring the magazines successively into operative relationship with the distributors, of a ridged font-selector bridge adapted to co-operate with notched matrices to determine the level at which such matrices pass a given point in their path towards the distributors, 90 a sliding member to which the bridge is rigidly attached, means adapted to slide said member in one direction and to normally retain the bridge in one operative position, means operated through the movement of alternate magazines into operative relationship with the distributors adapted to slide said member in the opposite direction to locate the bridge in another operative position, and matrices in successive magazines notched to pass the said given point at one and the same level when the bridge is 95 in the operative position determined by the movement of the respective magazine into operative relationship with one of the distributors, means adapted to convey to the said distributor matrices passing said point at that level, and means adapted to convey to the other distributor matrices passing said point at another level.

9. In a machine such as described, the combination with a column of magazines, two distributors adapted to co-operate simultaneously with two adjacent magazines and magazine-moving means adapted to bring the magazines successively into operative relationship with the distributors, of a rigid font-selector bridge adapted to co-operate with notched matrices to determine the level at which such matrices pass a given 125 130

point in their path towards the distributors, a sliding member to which the bridge is rigidly attached, means adapted to slide said member in one direction and to normally retain the bridge in one operative position, means operated through the movement of alternate magazines into operative relationship with the distributors adapted to slide said member in the opposite direction to locate the bridge in another operative position, matrices in successive magazines notched to pass the said given point at one and the same level when the bridge is in the operative position determined by the movement of the respective magazine into operative relationship with one of the distributors, and at another level when the bridge is in the operative position determined by the movement of the respective magazine into operative relationship with the other of the distributors, and means adapted to convey to the respective distributors matrices passing said point at the respective levels.

10. In a machine such as described, the combination with a column of magazines, two distributors adapted to co-operate simultaneously with two adjacent magazines and magazine-moving means adapted to bring the magazines successively into operative relationship with the distributors, of a font selector bridge having two selector rails, means controlled through the operation of the magazine-moving means adapted to move the bridge to two different operative positions alternately as the successive magazines are moved into operative relationship with the distributors and matrices in successive magazines notched to straddle the rails when the bridge is in the operative position determined by the movement of the respective magazine into operative relationship with the other of the distributors.

11. In a machine such as described, the combination with a column of magazines, two distributors adapted to co-operate simultaneously with two adjacent magazines and magazine-moving means adapted to bring the magazines successively into operative relationship with the distributors, of a font selector bridge having two selector rails, a sliding member to which the bridge is rigidly attached, means adapted to slide said member in one direction and to normally retain the bridge in one operative position, means operated through the movement of alternate magazines into operative relationship with the distributors, adapted to slide said member in the opposite direction to locate the bridge in another operative position, matrices in successive magazines notched to straddle the rails when the bridge is in the

operative position determined by the movement of the respective magazine into operative relationship with one of the distributors, and to ride over the rails when the bridge is in the operative position determined by the movement of the respective magazine into operative relationship with the other of the distributors, and means adapted to convey to one distributor matrices which straddle the rails and to the other distributor those which ride over the said rails.

12. In a machine such as described, the combination with a plurality of distributors, and an adjustable selector bridge for directing matrices to the respective distributors according to form, of a magazine containing matrices of a given form, means whereby said magazine may be operatively connected to one or another of the distributors, and automatic means for adjusting the selector bridge to effect the delivery of the matrices contained in said magazine to the particular distributor with which it is connected.

13. In the machine such as described, the combination with a plurality of distributors, and an adjustable selector bridge for directing matrices to the respective distributors according to form, of a magazine containing matrices of a given form and movable into operative relation to one or another of the distributors, and automatic means for adjusting the selector bridge to effect the delivery of the matrices contained in said magazine to the particular distributor with which it is brought into operative relation.

14. In a machine such as described, the combination of a matrix magazine movable to and from operative position, a distributor to cooperate with said magazine, an adjustable selector bridge for directing to said distributor matrices of one form or another, and means controlled by the movement of said magazine to operative position for adjusting the selector bridge to effect the delivery to the distributor of matrices of the form contained in said magazine.

15. In a machine such as described, the combination of a magazine containing matrices of a given form and replaceable in operative position by another magazine containing matrices of a different form, a distributor, an adjustable selector bridge for directing to said distributor matrices of one form or another, and means actuated by the replacement of the magazine for adjusting the selector bridge to effect the delivery to the distributor of matrices of the form contained in the substitute magazine.

16. In a machine such as described, the combination of a plurality of magazines containing matrices of different forms, a smaller plurality of distributors, an adjustable selector bridge for directing matrices to the respective distributors according to form,

means whereby the several distributors may be operatively connected to different groups of magazines, and automatic means for adjusting the selector bridge to effect the delivery to said distributors of matrices of the particular forms contained in the cooperating magazines.

17. In a machine such as described, the combination of a plurality of magazines containing matrices of different forms, a smaller plurality of distributors, an adjustable selector bridge for directing matrices to the

respective distributors according to form, means for moving the magazines to bring different groups thereof into operative relation to the several distributors, and means controlled by such movement of the magazines for adjusting the selector bridge to effect the delivery to said distributors of matrices of the particular forms contained in the operative group of magazines.

In testimony whereof I have affixed my signature hereto.

ROBERT DUDLEY CARTER.
